UNITED STATES PATENT OFFICE

JOSEPH R. EVES, OF BUFFALO, NEW YORK, ASSIGNOR TO FALLS ELECTRIC FURNACE CORPORATION, OF BUFFALO, NEW YORK, A CORPORATION OF NEW YORK

ELECTRIC FURNACE

Application filed January 20, 1928. Serial No. 248,175.

This invention relates generally to electric furnaces but more particularly to that type including a platform for the material to be heat-treated which is movable into and out of the furnace.

One of its objects is to provide a simple and inexpensive furnace of this character having positive means for sealing the load-carrying platform in place and thereby prevent undue loss of heat and afford a saving in the consumption of electric power.

A further object of the invention is to provide a trackless furnace of this type which is efficient and economical in operation and which minimizes the expense of the load-carrying equipment used in connecting therewith.

A still further object is the provision of simple means for supporting the load-carrying platform in a position for effecting the admittance of an even distribution of air to the furnace chamber for the purpose of gradually cooling the charge.

In the accompanying drawings:

Figure 1 is a front elevation of an electric furnace embodying my invention. Figure 2 is a vertical longitudinal section thereof on line 2—2, Fig. 1. Figure 3 is a transverse section on line 3—3, Fig. 2. Figure 4 is a horizontal section of the furnace taken in the plane of line 4—4, Fig. 2. Figure 5 is a transverse section, similar to Fig. 3, showing the work-carrying device in its elevated unsealed position. Figure 6 is a front end view of the wheeled truck.

Similar characters of reference indicate corresponding parts throughout the several views.

In the preferred embodiment of the invention shown in the drawings, 10 indicates the heating chamber and 11 the furnace body which may be constructed of any suitable refractory material. The heating chamber is closed on all sides with the exception of its front side, which is open and adapted to be closed by a vertically-movable door 12 suspended from chains 13 and operated in any approved manner. Applied to the walls of the heating chamber are the resistor elements 14 which may likewise be of any well known

construction. As shown in Figs. 2 and 3, the heating chamber is disposed above the floor line to provide an air space or compartment 15 beneath it, and to this end the walls of the furnace are supported on a metallic frame 55 which may be composed of longitudinal and transverse Z-bars 16 attached to upright channel bars 17.

The bottom of the heating chamber is preferably in the form of a movable platform or work-carrying device 18 which is capable of being moved longitudinally into and out of a suspended position in the compartment 15 thru the open front end of the furnace and which is adapted to be moved vertically into and out of its operative position to effect an air tight, sealed bottom for said chamber or to permit the admission of a certain amount of air thereto for cooling the charge after its desired heat treatment has been completed. 60 This platform is made of structural steel and insulating material and supported on legs 19. Any suitable means may be employed for moving the platform into and out of its operative position in the furnace, that shown in 65 the drawings, by way of example, consisting of a well known type of wheeled truck 20 having a vertically movable member 21 which functions to elevate the work-carrying platform.

This movable member may be actuated in any suitable manner, for example, by pinions 31 engaging corresponding racks 32 depending from such member, whereby upon turning the operating crank 33, the movable member 70 is raised or lowered.

Extending around the side walls and rear wall of the furnace adjacent to the compartment 15 is a sealing trough upon which the platform 18 is adapted to seat in its operative 75 position and thereby form an air-tight seal along these walls to eliminate heat losses within the furnace. This trough is preferably made of channel bars 22 containing sand or like material and secured to the inner sides 80 of the depending flanges 23 of the Z-bars 16. Depending from the sides and back of the platform 18 are sealing plates or aprons 24 which are adapted to enter the sand-filled 85 channel bars in the operative position of the 90

100

platform shown in Figs. 1, 2 and 3, and thereby effectively seal the lower end of the furnace chamber at its sides and back. For the purpose of sealing the lower front end of the furnace, the platform is provided across its front end with a transverse trough 25 constructed of a channel bar containing sand and the vertically movable door 12 is adapted to engage said trough in its closed position, as seen in Fig. 2. As shown in Figs. 1 and 4, the trough-bar 25 on the platform extends laterally beyond the ends of the longitudinal trough-bars 22 on the furnace which latter are disposed below the plane of the former, so that when the platform is in its operative position the lower end of the furnace chamber is sealed around its four sides.

In the use of the apparatus thus far described, assuming the furnace door 12 to be open, the platform 18 is loaded with its charge and then supported on the truck 20 and wheeled in an elevated position into the compartment 15 of the furnace, the elevating member 21 of the truck being raised to such a height as to allow the depending aprons 24 of the platform to clear the sand troughs 22 of the furnace. For the purpose of guiding the platform into its compartment, longitudinal guide rails 26 may be provided which are attached to the upright channel bars 17 and are disposed below the furnace trough-bars 22. After thus being moved into the furnace compartment 15, the elevating member of the truck is lowered to bring the platform-aprons 24 into engagement with the sand-troughs applied to the sides and rear end of the furnace, after which the door 12 is lowered to bring its lower end into engagement with the sand-filled trough 25 on the front end of the platform. With the platform properly set in a suspended position to effectually seal the furnace chamber 10, the truck 20 can be removed and be utilized for use in connection with other furnaces which may be ready for recharging or discharging of their contents. In removing the platform, the furnace door is opened and the truck is wheeled under said platform to raise it clear of the sealing troughs, after which it is pulled out of the furnace on the truck and unloaded.

By providing a suspended load-carrying platform and a sealing means of this character, the danger of losing sand during the insertion and removal of the platform into and out of the furnace is eliminated, thereby assuring at all times a positive and effective seal against heat losses from the furnace chamber.

In order to effect a gradual cooling of the charge after undergoing heat treatment, a uniform distribution of air is adapted to be admitted around the four sealed sides of the platform 18. This is preferably accomplished by providing an adjustable means for supporting the platform in a partially elevated

position to break its sealed joint. The means shown in the drawings consists of longitudinal base rails 27 disposed along opposite sides of the platform-compartment 15 of the furnace and attached at their front and rear ends to horizontally-foldable links 28 pivoted to base plates 29. These base rails are adapted to be moved to a position for allowing the legs 19 of the platform to rest thereon and hold the aprons 24 out of sealing engagement with the sand-troughs 22, as shown in Fig. 5. In seating the platform in such position, it is first elevated the required distance by the tiering truck 20, after which the base rails are shifted under the legs to support the platform, the truck being then removed and used for other duties. This arrangement permits of readily breaking the seal between the platform and the furnace and allows for the slow and even distribution of air thru all sides of the heating chamber.

This improved electric furnace provides for the efficient and economic handling of the materials to be treated by simple and inexpensive means which are so organized and arranged as to effectually seal the furnace against heat losses while the materials are undergoing heat-treatment, and which provides for the gradual cooling of the materials by breaking such seal and admitting an even distribution of air to the furnace chamber thru all sides thereof. Furthermore, this construction eliminates the use of expensive car and track equipment now employed in electric furnace installations and materially reduces the operating and maintenance costs of such furnaces.

I claim as my invention:

1. An electric furnace, comprising a heating chamber open at its bottom and having a door at its front end, a trough-shaped member containing a sealing material extending around the sides and rear end of the furnace chamber adjacent its bottom, a wheelless carrier for the material to be heat-treated movable into and out of the furnace and forming a closure for the bottom thereof in its operative position, means for conveying said carrier into and out of the furnace and for moving it vertically toward and from the trough-shaped member, and aprons depending from the sides and rear end of said wheelless carrier for sealing engagement with the material in said trough-shaped member.

2. An electric furnace, comprising a heating chamber open at its bottom and having a door at its front end, a trough-shaped member containing a sealing material extending around the sides and rear end of the furnace chamber adjacent its bottom, a wheelless carrier for the material to be heat-treated movable into and out of the furnace and forming a closure for the bottom thereof in its operative position, means for conveying said carrier into and out of the furnace, and for

- moving it vertically toward and from the trough-shaped member, aprons depending from the sides and rear end of said wheelless carrier for sealing engagement with the material in said trough-shaped member, and a second trough-shaped member containing a sealing material applied to the front end of said carrier and arranged to be engaged by the door in its closed position.
3. An electric furnace, comprising a heating chamber open at its bottom and having a door at its front end, a wheelless carrier for the material to be heat-treated movable into and out of the furnace and forming a closure for the bottom thereof, an upwardly-opening channel containing a sealing material extending around the sides and rear end of the furnace and disposed below its open bottom and below the top of said carrier, aprons depending from the sides and rear end of the carrier and engageable with the material in said channel for sealing the joint between said carrier and the furnace, and rests disposed in the bottom of the furnace and movable into and out of an operative position for supporting the carrier in a partially elevated position for breaking such sealed joint.
4. An electric furnace, comprising a heating chamber open at its bottom and having a door at its front end, a conveying device for the material to be heat-treated movable into and out of the furnace and forming a closure for the bottom thereof in its operative position, means for sealing the joint between said conveying device and the adjoining walls of the furnace, means for temporarily elevating said device for breaking said seal to admit air to the heating chamber for cooling the material undergoing heat-treatment, and means applied to the furnace for supporting the device in its elevated position.
5. An electric furnace, comprising a heating chamber open at its bottom and having a door at its front end, a wheelless carrier for the material to be heat-treated movable into and out of the furnace and forming a closure for the bottom thereof, upwardly-opening channels containing a sealing material extending around the sides and rear of the furnace and disposed below the top of the carrier, aprons depending from the sides and rear end of the carrier and engageable with the material in said channel for sealing the joint between said carrier and the furnace, and supporting rails adjustably mounted at the sides of the furnace for sustaining the carrier in a position to break the seal between it and the channels.

JOSEPH R. EVES.
